(57) CLAIM

The ornamental design for a bird plush, as shown and described.

DESCRIPTION

FIG. 1 is a front left perspective view of a bird plush showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines depict portions of the article that form no part of the claimed design. The short lines of uneven length represent a plush appearance and are not intended to indicate differences in plush level.
